(57) **CLAIM**

The ornamental design for a drill, as shown and described.

DESCRIPTION

FIG. 1 is a perspective view of a drill according to the present invention;

FIG. 2 is a front view of the drill of FIG. 1;

FIG. 3 is a back view of the drill of FIG. 1;

FIG. 4 is a right side view of the drill of FIG. 1;

FIG. 5 is a left side view of the drill of FIG. 1;

FIG. 6 is a top view of the drill of FIG. 1; and,

FIG. 7 is a bottom view of the drill of FIG. 1.

The portions shown in broken lines form no part of the claimed design but are provided for completeness.

1 Claim, 5 Drawing Sheets

FIG. 1

FIG. 2

FIG. 3

FIG. 4

FIG. 5

FIG. 6

FIG. 7
